WIRE FORMED PALLET

James D. Wilson, Garden Grove, Calif., assignor to
Banner Metals, Inc., Compton, Calif.

Filed Nov. 3, 1972, Ser. No. 303,520

Term of patent 14 years

Int. Cl. D9—99

U.S. Cl. D12—53

Fig. 2

Fig. 3

FIG. 1 is a perspective view of a wire formed pallet showing my new design;

FIG. 2 is an end elevational view thereof; and

FIG. 3 is a top plan view thereof.

I claim:

The ornamental design for a wire formed pallet, substantially as shown.
